UNITED STATES PATENT OFFICE.

GEORGE E. WITT, OF SAN FRANCISCO, CALIFORNIA, ASSIGNOR TO FRANK H. BATES, OF SAN FRANCISCO, CALIFORNIA.

VAPOR-GENERATOR.

SPECIFICATION forming part of Letters Patent No. 772,488, dated October 18, 1904.

Application filed February 11, 1903. Serial No. 142,910. (No model.)

To all whom it may concern:

Be it known that I, GEORGE E. WITT, a citizen of the United States, residing at 2952 Folsom street, San Francisco, in the county of San Francisco and State of California, have invented certain new and useful Improvements in Vapor-Generators; and I do hereby declare the following to be a full, clear, and exact description of the same, such as will enable others skilled in the art to which it appertains to make and use the same.

My invention relates generally to improvements in gas-generators; but to be more specific it is a generator designed to utilize the heavy viscous crude oils now so extensively found on the Pacific coast.

In the majority of generators now on the market it has been found almost impossible to practically cope with the gummy residue from the oil, as it rapidly fouls the generator and makes thorough cleansing a frequent necessity. In my generator I overcome these objections by providing means for automatically clearing the parts of this residue and in addition have aimed to bring to a greater degree of perfection the operation and general efficiency of the machine.

To the attainment of the foregoing and other useful ends my invention consists in matters hereinafter set forth.

In the accompanying drawings, in which similar numerals of reference designate corresponding parts, Figure 1 is a side elevation of the complete device, a portion of the outer wall being broken away to show the relative arrangement of the interior parts. Fig. 2 is a transverse section taken in the direction of the arrows in Fig. 1.

I will now set forth the construction of my generator and subsequently explain the operation of the same.

The main body of the device consists of a hollow drum 2, formed with a spreading hollow base, as shown in Fig. 2. This drum 2 is cast with one end closed, while the opposite head is held in place with the square-headed screws *a*. Adapted to revolve within the drum 2 and on suitable packed bearings

in the heads thereof is the inner hollow drum 1. The shafts 7 and 9, which are connected to opposite ends of the inner drum 1, are hollow and form a continuous conduit to and from the interior of the drum. Keyed to the shaft 7 is the small worm-gear 13, to which is transmitted motion from the belt-wheel 14. The worm and gear are shown by means of dotted lines in Fig. 2.

The remaining elements of the device I will explain as the operation of the generator is followed.

Assuming that oil is fed to the interior of the drum 2 through the pipe 5 until it reaches the level indicated by the dotted line 11 and that the drum 1 is slowly revolving, it is manifest that as the drum 1 is partly immersed in the oil the latter will cling to its outer periphery and follow its upward movement. Now as the exhaust from the engine is passed through the drum 1 by means of the hollow shafts 7 and 9 the drum will become heated and the clinging oil transformed into vapor, which is led to the engine through the pipe 3. As this oil is heated a thick sticky residue clings to the periphery of the drum 1, and if some means were not provided by which to cleanse this drum the device would be of very little practical value. I accomplish the automatic cleansing of this drum by means of the horizontal knife 10, which bears against the lowest level of the drum and scrapes its surface clean before it ascends with a fresh coating of oil. This thick material drops to the base of the drum 2, from which it is led by the drain-cock 4. In order to retain a constant flow of oil, I have provided the small pipe 6, which has a neck reaching to the desired level of the oil. It is manifest that by the use of this pipe the level is preserved and the comparatively lighter oil kept in contact with the revolving drum. The cock 8 is provided as an air-inlet to the interior of the outer drum, while the stuffing-box 12 permits of the union between the stationary and revolute pipe from the engine.

It will be readily seen from the foregoing description that I have provided a very sim-

ple and effective generator automatic in its action and one in which the parts are kept constantly free from objectionable matter.

Having thus fully described my invention, 5 what I claim, and desire to secure by Letters Patent, is—

1. A device of the class described consisting of an outer stationary drum, a revolving drum within said former drum, hollow shafts leading through said outer drum to the interior of said revolving drum, an oil-inlet to said outer drum, an oil-outlet to preserve the level of the oil relative to said revolving drum, a vapor-outlet from said stationary drum and 15 means for conducting the heating medium to the revolving drum substantially as and for the purpose set forth.

2. A device of the class described consisting

of an outer stationary drum, a revolving drum within said former drum, hollow shafts leading through said outer drum to the interior of said revolving drum, a stationary knife within said stationary drum and bearing against the periphery of said revolving drum, an oil-inlet to said outer drum, an oil-outlet to preserve 20 the level of the oil relative to said revolving drum, a vapor-outlet from said stationary drum and means for conducting the heating medium to the revolving drum substantially as and for the purpose set forth.

In testimony whereof I affix my signature in presence of two witnesses.
